STUART PARMELEE MILLER, OF GLEN RIDGE, NEW JERSEY, ASSIGNOR TO THE BARRETT COMPANY, OF NEW YORK, N. Y., A CORPORATION OF NEW JERSEY

METHOD OF PRODUCING CREOSOTE OILS

Application filed July 16, 1927. Serial No. 206,366.

This invention relates to the production of creosoting compositions.

Creosote oils are commonly produced by the distillation of tar in ordinary tar stills.

5 In order to obtain high yields of creosote oils, the distillation of the tar must be carried to a high temperature. Such distillation of tar, particularly at high temperatures, is accompanied by a very considerable decomposition 10 of oil constituents, with resulting increase in pitch residue and in carbon content of the pitch residue. The pitch residue produced, particularly where the distillation is carried to a high temperature, is high in carbon content, a large part of which is produced by decomposition during the distillation from oil constituents contained in the tar undergoing distillation.

This distillation of tar for the production 20 of creosote oils is carried out at tar distillation plants which are frequently remote from the coke ovens where the tar is produced, and the tar must be shipped from the coke oven plant to the tar distillation plant with added 25 cost of transportation and expense and loss of handling and rehandling the tar.

The tar, which is carried in the coke oven 30 gases as they leave the ovens, is recovered therefrom by cooling the gases, usually with ammonia liquor, or ammonia liquor and tar, to separate out the tar constituents from the gases. The tar thus separated is then shipped, as above noted, to the tar distillation plant, and there subjected to distillation 35 in tar stills for the production of creosote oils, etc., and pitch residues.

The present invention provides an improved method of producing creosote oils whereby the production of tar from the coke 40 oven gases and its subsequent transportation to the tar distillation plant and its distillation there to produce the creosote oils are eliminated and in which the creosote oil is produced directly at the coke oven or other 45 coal distillation plant in a simple and advantageous manner and with materially increased yield of creosote oil.

According to the present invention, the hot 50 coal distillation gases as they come from the coke ovens or retorts, are subjected to a regu-

lated cooling such that they will carry in suspended form particles of pitch of relatively high melting point, and the gases are then subjected to a cleaning treatment for the removal therefrom of the suspended pitch particles, while leaving in the gases in vapor form the desired oil constituents, and particularly heavy oil constituents. The cleaned gases, containing such oil constituents, are then subjected to cooling to a low temperature to separate a composite oil therefrom, which will be a balanced oil containing both heavy and lighter oil constituents, but which as a whole will be suitable for use as a creosote oil. The gases, after the separation of the oil 60 therefrom, are then passed through the ammonia absorber or saturator, to remove ammonia therefrom, and they are then finally passed through a scrubber or absorber for the light oils, such as benzol. By proceeding 65 in this way, there is directly separated and recovered a creosote oil, in a single operation, which is available for use as a valuable creosote oil, without further treatment.

The hot coal distillation gases from a coke 70 oven leave the oven at a high temperature, around 600° to 700° C. or higher. These gases are subjected to a regulated cooling treatment to cool them to a regulated lower temperature, for example, a temperature 75 around 200° C., or around 250° C. This cooling of the hot coke oven gases can be effected by passing through pipes exposed to the atmosphere or by introducing regulated amounts of a cooling agent therein, for 80 example, a limited and regulated amount of ammonia liquor, which, by vaporization, will lower the temperature of the gases. If an ordinary collector main is employed for collecting the gases from a number of ovens, 85 the cooling may take place in such collector main and in the pipes leading from the coke ovens to it, and this cooling may be assisted by a limited and regulated ammonia liquor spray.

90 After the gases have been cooled to a regulated lower temperature, but a temperature still sufficiently high to carry the desired oils in the form of vapors and to carry in suspension pitch particles of the desired high melt- 95 100

ing point, the gases are subjected to a cleaning treatment for the removal of the pitch particles therefrom, while leaving the oil vapors in the gases. This cleaning of the gases 5 can be effected by a sufficiently intimate scrubbing or washing of the gases with pitch of similar temperature and composition to that of the particles carried in the gases; but it is more advantageously effected by means of 10 an electrical precipitator through which the gases are passed at the regulated temperature, since the electrical precipitator will throw the pitch particles out of suspension, while leaving the oil vapors in the gases, and 15 giving clean gases carrying the clean oil vapors in suspension or admixture with them. This cleaning of the gases separates therefrom a pitch product, the melting point of which can be regulated by regulating the 20 temperature to which the gases are cooled and at which they are cleaned. If, for example, a pitch of melting point around 300° F. is desired, the temperature to which the gases are cooled should be regulated so that the 25 pitch particles carried in suspension therein will have the desired melting point. If pitch of a higher or lower melting point is desired, this can be obtained by increasing or decreasing the temperature of the gases at the time 30 they are subjected to the cleaning treatment for the separation of the pitch particles therefrom. The lower the temperature to which the gases are cooled, the lower the melting point of the pitch, since, with lowering of 35 temperature, some of the heaviest oil or grease or resin constituents originally carried in the gases in the form of vapors, are condensed as liquids and included with the pitch particles separated from the gases. At 40 higher temperatures, less of these constituents will have been condensed, and more of them will be carried in vapor form through the precipitator during the cleaning treatment.

The pitch product produced by the cleaning 45 of the gases will be a directly recovered pitch of low carbon content, and in particular it will be free or relatively free from decomposition products formed by subjecting tar to distillation in ordinary externally heated tar stills. The pitch can be produced of regulated melting points such that it can advantageously be employed directly for purposes where a hard or high melting point pitch is desired. It may also be blended with other 50 pitch or tar products or oils for special purposes, where its low carbon content makes it valuable.

The cleaned gases from which the pitch particles have been separated by the cleaning treatment will still contain a wide range of oil constituents, including heavy high boiling oil constituents, and constituents which are incapable of distillation, by ordinary distillation methods, without decomposition. These 55 gases will be clean gases, and the vapors car-

ried thereby will be clean vapors, in the sense that the gases and vapors will be free, or substantially free from heavy tar and pitch particles, which are carried in suspension in ordinary coke oven gases and which contaminate and form part of the tarry oil products 70 commonly produced from such gases.

According to the present invention, these clean gases, carrying vapors of a wide range of oils therein, are subjected to condensation 75 to separate creosote oil therefrom, or an oil composition valuable for use as a creosote oil. Where the gases are cleaned at a high temperature, they will still contain in vapor form, heavy or high boiling oil constituents, and they may also contain in considerable amount constituents which, by themselves, would be of a greasy or resinous character at ordinary temperature, but which when 80 condensed with the lighter oil constituents, blend therewith to form a homogeneous creosote oil composition.

The cooling of the gases to separate the creosote oil therefrom may advantageously be effected in a single condenser or in a series 85 of condensers such as are commonly employed at coke oven plants for the condensation of light tar or tarry oils from ordinary coke oven gases. Such condensers may contain, for example, several stages and may be 90 either indirectly cooled or directly cooled by direct contact with cooling liquid. The cooling is advantageously carried to a low temperature to separate as much as possible of the oil constituents therefrom, for example, a 95 temperature around 25° to 35° C., at which 100 temperature most of the oil vapors will be separated except those subsequently recovered in the light oil scrubbers or absorbers.

By carrying the condensation to a low temperature, there will be included in the product light oil constituents, which, by themselves, would have a relatively low boiling point. Nevertheless, where heavy oils are also included in the product, the light oil 105 constituents blend therewith, so that the composition as a whole will give only a small percentage of oil when subjected to distillation to a temperature up to around 210° C., for example, not more than five per cent at 210° 110 C., although in some cases a somewhat increased amount may distill at such temperature. Similarly, when subjected to distillation up to 235° C., the oil will not give more than about 25 per cent of distillate, although 115 in some cases the amount may be somewhat higher, for example, up to around 35 or 40 per cent. Where, however, the heavy high boiling oil constituents, including grease and 120 resin constituents, are retained in the gases and condensed as part of the creosote oil there will result a blended product of a composite character and of a balanced character, the heavy oils balancing the lighter oils and giving 125 a well balanced creosote oil composition. 130

The relative proportion of heavy constituents and of light constituents can be varied and regulated by regulating the temperature of the cleaning operation at which the pitch is removed from the gases and the temperature of the condensing operation. Different coal distillation gases may differ materially from each other in their vapor content and to some extent in the character of the vapors and the proportions of the vapor constituents which they contain, depending, for example, on the character of the coal subjected to the coking or distillation, the manner in which the coking or distillation is carried out, whether with rapid or slower coking, the temperature of the coking operation, the type of coking retort, etc. However, by cooling the gases to a regulated temperature and separating the pitch particles therefrom, it can readily be ascertained whether the pitch separated is of the desired melting point, and if a higher or lower melting point is desired, the temperature of the cleaning can be increased or decreased. If, for example, a pitch of a melting point around 300° F. is desired, the cooling can be regulated so that a pitch of this melting point will be separated when the gases are cleaned in the electrical precipitator. A temperature around 250° C. may be sufficient with some coke oven gases to give a pitch of such melting point, although the temperature may vary somewhat with different coke oven gases. The proper temperature can readily be ascertained, as above noted, by noting the melting point of the pitch and increasing or decreasing the temperature in case a higher or lower melting point pitch product is desired and a correspondingly increased or decreased content of heavy oil vapors in the cleaned gases and in the creosote oils to be recovered therefrom. Where pitch of a higher melting point is desired, for example, around 400° F. or higher, a higher temperature will be maintained during the cleaning operation and a materially increased portion of oils will be recovered, including heavy oil or grease or resin constituents, which will blend with the lighter oil constituents in the new composite creosote oil product. Where a softer pitch is desired, for example, a pitch having a melting point around 200° F., a correspondingly lower temperature can be employed for the cleaning treatment, and the cleaned gases will carry less of the heavy oil constituents, and the final temperature of condensation may be somewhat higher, so that less of the lighter oils will be included in the product, if a somewhat heavier creosote oil is desired.

The cooling of the cleaned gases for the separation of the creosote oil therefrom may, as above noted, be carried out in either direct or indirect coolers or condensers and in a single fraction or series of fractions, part or

all of which may be combined to give the creosote oil. Where a single total condenser is employed for condensing the gases, e. g., from a temperature around 200 or 250° C. to a temperature around 25° to 35° C., there will be directly obtained a composite oil product containing a wide range of oil constituents, including both heavy high boiling constituents and lighter low boiling constituents, which, however, in the blended and balanced product will so blend that the product as a whole will not begin to distill until it reaches, e. g., a temperature around 200° C., and will give only small percentages at higher temperatures, e. g., around 210° C. The inclusion of the heavy constituents in such a product makes possible the utilization of the total oil content recovered from the gases, including the lighter oil constituents, to give a balanced creosote oil.

The cooling of the gases can advantageously be carried out with direct introduction of water, or ammonia liquor free from tar, into the gases. Inasmuch as the gases themselves are free from heavy tar and pitch constituents, the water employed for cooling them will give an ammonia liquor free from tar, and which, when it has increased in ammonia content to the desired extent, can be subjected to distillation or treatment for the recovery of ammonia therefrom without the objections incident to the distillation of tar-contaminated liquor. When water or ammonia liquor is employed, the gases will be rapidly cooled to a low temperature, so that the entire cooling operation can be carried out in one or two stages, down to a temperature around 25° to 35° C.

After the condensation of the clean oils therefrom, the gases, which will be clean gases, free from suspended tar particles, are then passed to the ammonia absorber or saturator, and the ammonia still carried in the gases will be recovered therefrom, e. g., as ammonia liquor or ammonium sulphate, which will be free from tar contamination. The completion of the separation of suspended oil particles from the gases can be effected by a further cleaning of the gases with an electrical precipitator at a low temperature, around 25° to 35° C., before they enter the ammonia absorber or saturator. After the gases leave the saturator or absorber, they then pass through the scrubber or absorber for light oils, leaving clean gases for use for fuel or other purposes.

The creosote oil directly recovered from the coke oven gases, according to the present invention, differs materially from the creosote oils produced as distillate oils by distilling coal tar in ordinary tar stills. It contains oil components which, in the distillation of tar in ordinary tar stills, are decomposed and converted into carbon or pitch. These constituents which are decomposed and lost in

ordinary tar distillation methods for making creosote oils, are retained in the creosote oil prepared according to the process of the present invention. This creosote oil accordingly represents a greatly increased yield of creosote oil, directly recovered from the coke oven gases, as compared with the yield of creosote oil obtained by the recovery of tar from the gases and distillation of the tar in ordinary tar stills.

The composition of the creosote oil can be somewhat varied and regulated, where this is desired, to give a heavier or a lighter creosote oil, by regulating the temperature of cleaning at which the pitch is separated and the temperature of cooling for completing the condensation of the oils from the gases. Even where the pitch separated from the gases has a melting point around 160° or 170° F., the total oil subsequently condensed from the clean gases may be employed as a creosote oil. Where a higher melting point pitch is recovered at a higher temperature of cleaning of the gases, for example, a pitch of melting points around 200° F., the total oil recovered from the gases can also be employed as a creosote oil and will be a somewhat heavier oil than that above mentioned. With a still higher melting point pitch separated at a higher temperature, for example, a pitch of melting point around 300° F., the total oil recovered will be a rather heavy creosote oil, while with the separation of a still higher melting point pitch around 400° F., melting point, at a higher temperature cleaning of the gases, a materially increased yield of creosote oil will be obtained and the entire oil will be a heavy creosote oil, which will be valuable for uses where a heavy oil is desired. Because of the inclusion in the creosote oil of the heavy constituents, including heavy oils of boiling point above 350° C., and including also constituents which by themselves would be of a greasy or resinous character, the composition has the advantage that when employed for creosoting purposes, or as part of a creosoting composition, it supplies not only lower boiling constituents which may slowly vaporize, but relatively large amounts of higher boiling constituents which remain as a valuable residue in the material creosoted.

In ordinary externally heated stills of e. g. 10,000 gallons capacity in which successive changes of tar are distilled to make pitch and distillate oils, the oil yield obtained in distilling tar to produce a pitch of 170° F. m. p. is only about 33% of the tar distilled; in distilling tar to produce pitch of 200° F. melting point, the oil yield is around 38%; in distilling to 300° F. m. p. pitch the oil yield is around 44%; and coking may begin to take place before a pitch of 400° F. m. p. can be obtained. According to the present process, radically increased yields of a different and

superior oil product can be recovered. For example, when pitch of around 170° F. m. p. is directly separated from coke oven gases, according to the present process, an oil yield of around 48% or higher is obtained; when 200° F. m. p. pitch is produced, the oil yield is around 55% or higher; when 300° F. m. p. pitch is produced, the oil yield is around 70% or higher; when 400° F. m. p. pitch is produced the oil yield is around 80% or higher; and it is possible to produce pitch of even higher melting point and obtain even higher yields of creosote oils. These radically increased oil yields are accompanied by a radical reduction in the amount of pitch of corresponding melting point, with directly recovered pitches will be of different composition and in particular will be of relatively low carbon content. In distilling tar in simple tar stills a large amount of decomposition takes place and the pitch produced contains a large amount of the resulting decomposition products, whereas in the present process the pitch is directly recovered without subsequent distillation and accompanying decomposition and formation therein of such decomposition products.

As compared with ordinary methods of producing creosote oil, it will accordingly be seen that the present process avoids the necessity of separating and collecting tar from the coke oven gases and the handling and shipment of this tar, and its subsequent distillation, thus greatly simplifying and reducing the expense of producing the creosote oil, while also giving a radically increased yield of creosote oil of new and improved composition, containing constituents not contained in ordinary distillate oils; while simultaneously there is produced a relatively high melting point pitch which is nevertheless of relatively low carbon content and which represents a materially lower proportion or percentage of the total tar content of the coke oven gases than is represented by the pitch residue from ordinary tar stills distilling a corresponding amount of the tar.

The invention will be further described in connection with the accompanying drawings, which illustrate, in a somewhat conventional and diagrammatic manner, an apparatus suitable for the practice of the process of the invention; but it is intended and will be understood that the invention is illustrated by, but is not limited to the specific apparatus and procedure described.

In the accompanying drawings

Fig. 1 shows in a conventional and diagrammatic manner, part of a by-product recovery system of a coke oven plant, modified for the practice of the process of the invention, and

Fig. 2 is an elevation partly in section of one form of electrical precipitator illustrated in Fig. 1, the specific construction of

the precipitator being that of the McCloskey patent, No. 1,752,920 issued April 1, 1930.

In the apparatus illustrated a coke oven block is shown conventionally at 1, having the usual uptake pipes 2, leading to a collector main 3 common to a number of ovens. The gases from the collector main pass through the main or pipe 4 to an electrical precipitator 5, in which the gases are treated at the required high temperature to separate pitch particles therefrom and to leave clean gases carrying the clean oils in the form of vapors.

The hot clean gases from the electrical precipitator pass through the cross-over main 34 to the condensers indicated conventionally at 35, in which the hot gases are cooled to separate the clean oils therefrom by introduction of cooling liquid such as water through the pipes 40. The condensers shown are the type in which the gases enter first at the bottom of one compartment or condenser and are cooled therein by direct contact with a cooling liquid such as water or ammonia liquor, and then passed to the bottom of the next compartment or condenser, where they are further cooled by direct contact with cooling liquid, after which the gases pass to the exhauster and thence to the ammonia saturator and light oil scrubber. In the drawings the exhauster is indicated at 36, the ammonia saturator at 37 and the light oil scrubber at 38, the gases then flowing through the line 39 to a gas storage or to a place of use.

The condenser 35 is shown as having the outlet at the bottoms of both compartments leading to the same receptacle or decanter 26, this arrangement being such that the total condensate in the condenser will be collected together as a creosote oil. The condensate that forms in the cross-over main 34 may be collected in the receptacle or decanter 27, while that condensing in the outlet pipe from the condensers may be collected in the further receptacle or decanter 28. The oils from all of these decanters or receptacles may be blended to make a composite product containing all of the oils condensed from the gases; or the oils from the separate compartments of the condensers may be collected separately and mixed in desired proportion.

The clean oils condensed from the gases may be extracted for the recovery of tar acids therefrom, although it is not necessary to extract them, and the oils can be utilized directly without further treatment as merchantable creosote oils of improved properties for creosoting purposes, or for use in making creosote compositions by blending with other ingredients, such as tar, where a solution of tar in oil is desired.

Where tar acids are to be recovered from the creosote oil, the entire oil can be extracted, to give substantially the total tar acid content of the oil, including higher phenols or tar acids as well as lower phenols or tar acids, in which

case the extracted creosote oil will be free or substantially so from tar acids, but will otherwise be practically unchanged in composition. Instead of extracting the total oil, only the lighter fraction or fractions rich in lower tar acids may be extracted, and the resulting neutral oil blended back with the heavier unextracted oil, in which case the resulting creosote oil will be relatively free from lower boiling tar acids. The extraction of tar acids, where this is to be effected, may be, for example, with a ten per cent solution of caustic soda brought into intimate intermixture with the oil, and by setting free the tar acids from the resulting carbolate solution, e. g. by treatment with carbon dioxide.

The electrical precipitator illustrated in Fig. 5 comprises a shell 5, for example, of cylindrical form, having a gas inlet 6 near the lower end thereof, and a gas outlet 7 near the upper end, this inlet and outlet being for the introduction of the hot coke oven gases and the exit of the hot cleaned gases. A baffle 8 partially separates the lower chamber 9 from the electrode chamber 10. A plurality of tubes 11 is supported in headers 12 and forms the positive electrode of the separator, the shell of which is grounded. Bus-bar 14 supports the electrodes 15 in spaced relation to the sides of the tubes 11. The bus bar 14 extends through openings 16 into chambers 17, in which insulators 18 support the bus bar which is connected to any suitable source of high tension current. Coils 19 may be disposed in the chambers 17 around the insulators 18 for heating these chambers when desired and the heating medium may also be passed through the jacket surrounding the tubes by means of connections 22 and 23; or the space between the tubes may be filled with insulating material to reduce loss of heat by radiation or cooling while the gases are passing through the precipitator.

In the operation of this electrical precipitator, the gas enters through the inlet 6, passing around the baffle 8 and then upwardly through the tubes 11, where the high tension discharge between the electrodes 15 and the tubes 11 effects removal of substantially all solid and suspended particles from the gases in the form of a directly recovered high melting point pitch which flows down over the baffle 8 into the chamber 9, and thence to the outlet pipe 20. Manholes 21 permit access to the interior of the precipitator.

In the operation of the apparatus illustrated, the coke oven gases from the individual ovens enter the collector main and then pass through an electrical precipitator at a high temperature, and are there cleaned and entrained pitch and other particles removed therefrom, leaving clean hot gases containing the oils in vapor form. The gases may be cooled in the collector main by a regulated and limited spray of ammonia liquor, or am-

monia liquor may be flushed through the bottom of the main, where it will come in surface contact with the hot gases and cool them to some extent while keeping the main clear 6 from obstructions due to accumulated tar or pitch. Excessive cooling of the gases should be avoided, although some local over-cooling may take place. The average temperature of the gases, however, when they leave the collector main and pass through the electrical precipitator should be sufficiently high to give a pitch of the desired high melting point and to leave oils of the desired character in vapor form. Owing to local over-cooling, the 10 product separated in the collector main may be a heavy tar admixed with ammonia liquor, which will be drawn off into the receptacle or decanter 30.

The regulation of the temperature in the 20 collector main may also be effected by circulation of hot pitch through the collector main so as to avoid excessive cooling, and to keep the main free from accumulation of hard pitch. By circulating a sufficient amount of 25 hot pitch through the collector main, the main can be kept free from such obstructions, and any tar or pitch constituents separated in the main will be blended with the circulating pitch. Some distillation of this pitch 30 may take place with resulting increase in vapor content of the gases, and tar may be added to the pitch and may likewise undergo distillation. Such distillation will result in enrichment of the gases in the vapors distilled 35 from the tar or pitch, and such enrichment will materially change the temperature of operation of the electrical precipitator to separate a pitch product of a particular melting point. With such enrichment, the temperature 40 of the gases passing through the precipitator must be materially higher to give a pitch of the same melting point, than where normal coke oven gases are employed without such enrichment; and with any large 45 amount of distillation of tar and enrichment of the gases, a very much higher temperature for cleaning of the gases should be employed to retain the increased amount of vapors in the vapor state, and to give a pitch of the de- 50 sired high melting point. Where ammonia liquor in limited amount is employed in the collector main, the gases will not be enriched, but will carry only their normal tar and vapor content. Pipes for leading cooling liquid 55 to the collector main and goose-neck are indicated at 41, and the outlet for the tar or pitch etc. at 24 leading to receptacle 25.

In order better to regulate the temperature 60 of the gases, the collector main and individual uptake pipe from the individual oven to the collector main and also the connecting main or pipe 4 in the electrical precipitator may be insulated to reduce and regulate the loss of heat due to atmospheric 65 cooling.

With gases entering the electrical precipitator at a regulated temperature, for example, around 200° C. or 250° C., or such a regulated temperature that a pitch of the desired melting point will be obtained, e. g., 70 a pitch of melting point of 300° F. or 400° F., there will be recovered from the precipitator a pitch of the desired melting point, while the gases will leave the precipitator still at a high temperature and carry a large 75 amount of oil in vapor form, including heavy or high boiling oil constituents, a considerable amount of which will boil above 350° C., and some of which may, as above noted, be of a grease-like or resin-like character in an 80 isolated state.

The clean gases leaving the precipitator at a high temperature, will then pass to the condensers 35, and be there cooled, and the oils condensed therefrom in the form of clean 85 oils with increased yield as compared with the yield of distillate oils obtained by distilling coal tar in ordinary stills. By condensing all of the oil constituents together, including both light and heavy oil constituents, 90 a balanced product is obtained, so that the product as a whole can be employed as a creosote oil, thus giving the maximum yield of creosote oil as a directly recovered oil of distinctive and improved composition as compared with ordinary coal tar distillate oils. 95

References to pitch melting points refer to melting points determined by the method described in "Methods of analysis used in the coal tar industry" by J. M. Weiss in the Journal of Industrial and Engineering Chemistry, Vol. 10, No. 10, October 1918, page 817. Creosote oil boiling points refer to boiling 100 points determined by Method D-246-30 of the American Society for Testing Materials. 105 I claim:

1. The method of treating coal distillation gases, which comprises subjecting them to a regulated cooling treatment to cool them to a temperature such that pitch particles of relatively high melting point are carried in suspension therein, while creosote oils are contained in vapor form, then cleaning the gases without cooling them to separate pitch particles therefrom and to leave clean gases containing creosote oil vapors and cooling the cleaned gases to separate therefrom an oil suitable for use as creosote oil, before passing the gases through an ammonia absorber. 115

2. The method of treating coal distillation gases, which comprises subjecting them to the action of an electrical precipitator at a temperature such that pitch particles of relatively high melting point are separated from the gases, while oil constituents, including high boiling oil constituents, are retained in the vapor state and cooling the resulting cleaned gases to separate therefrom the creosote oil containing such high boiling constit- 120 125 130

uents, before passing the gases through an ammonia absorber.

3. The method of treating coke oven gases whereby creosote oils are produced directly therefrom, which comprises subjecting the coke oven gases to a cleaning treatment at a sufficiently high temperature to separate therefrom a pitch product having a melting point in excess of about 150° F. and cooling the resulting cleaned gases to separate therefrom an oil suitable for use as a creosote oil, before passing the gases through an ammonia absorber.

4. The method of treating coke oven gases whereby creosote oils are produced directly therefrom, which comprises subjecting the coke oven gases to a cleaning treatment at a sufficiently high temperature to separate therefrom a pitch product having a melting point in excess of about 200° F. and cooling the resulting cleaned gases to separate therefrom an oil suitable for use as a creosote oil, before passing the gases through an ammonia absorber.

5. The method of treating coke oven gases whereby creosote oils are produced directly therefrom, which comprises subjecting the coke oven gases to a cleaning treatment at a sufficiently high temperature to separate therefrom a pitch product having a melting point in excess of about 300° F. and cooling the resulting cleaned gases to separate therefrom an oil suitable for use as a creosote oil, before passing the gases through an ammonia absorber.

6. The method of treating coke oven gases whereby creosote oils are produced directly therefrom, which comprises subjecting the coke oven gases to a cleaning treatment at a sufficiently high temperature to separate therefrom a pitch product having a melting point in excess of about 400° F. and cooling the resulting cleaned gases to separate therefrom an oil suitable for use as a creosote oil, before passing the gases through an ammonia absorber.

7. The method of treating coke oven gases whereby creosote oils are produced directly therefrom, which comprises subjecting the coke oven gases to cleaning with an electrical precipitator at a sufficiently high temperature to separate therefrom a pitch of relatively high melting point and to leave oils, including oils of high boiling point above 350° C., in the form of vapors and cooling the resulting cleaned gases to separate therefrom an oil suitable for use as a creosote oil, before passing the gases thru an ammonia absorber, such cooling including cooling of the gases to a temperature around 25° to 35° C.

In testimony whereof I affix my signature.
STUART PARMELEE MILLER.
